SIMON GROSSINGER, ALL OF SCRANTON, PENNSYLVANIA.

LAMP REFLECTOR

Application filed December 29, 1927. Serial No. 243,336.

This invention relates to improvements in reflectors, particularly of a mirror type adapted to be used in connection with gas lamp testers and the like.

5 An object of this invention is to provide a reflector of the mirror type which may be easily adjusted to a gas lamp tester or other suitable device.

The prime object of this invention is to 10 provide a mirror reflector adapted to aid in reading the gas lamp tester, whereby the lamp may be lowered into a manhole or any other opening where there is supposed to be gas, or the like, and the mirror reflector may 15 be so adjusted that the reading may be easily accomplished, thereby avoiding the danger of being overcome by objectionable fumes, which often occurs when it is found necessary to personally enter the manhole or opening.

20 Other objects of this invention will appear from the following detailed disclosure of the device and is clearly disclosed in the single sheet of drawings, which are herewith made a part of this application.

25 In the drawings—

Figure 1 illustrates a perspective view of a gas lamp tester showing the mirror reflector in assembled relationship thereto.

Figure 2 represents a side elevational view 30 of the lamp tester showing the reflector in adjusted position thereon.

Figure 3 illustrates a top plan view of the reflector detached from the lamp tester.

Figure 4 illustrates a bottom plan view of 35 the reflector detached from the lamp tester.

Figure 5 illustrates a detailed view of the clamping member for holding the reflector in operable relationship with the lamp tester.

This invention provides an adjustable reflector in combination with a gas lamp tester, 40 or other suitable device upon which the reflector may be used to advantage, comprising a gas lamp tester having a main body portion 1, a base portion 2, the main body and base portions being held in spaced relationship by means of a plurality of rods, such as 3, 4, 5 and 6, made of any suitable material. Between the main body and base portions 1 and 2 is also commonly positioned a glass or other 45 transparent portion 7 made of any shape 50

adaptable for the purpose and formed to enclose the flame or jet and other features required in a gas lamp tester. The transparent portion 7 is preferably of tubular shape and is adapted to have longitudinally positioned thereon a coating 8 of black material, such as shellac, paint or otherwise.

55 Removably positioned within the base portion 2 of the lamp is a container 9 for holding the fuel adapted to supply the wick member 10, which functions to produce, when ignited, the necessary jet or flame for the lamp. Supported by the container 9 and extending a suitable distance above the wick 10 is a frame 11, made of wire or otherwise for holding in proper position the sensitive testing filaments 12. The main body or upper portion of the lamp 1 is adapted to be constructed in such a manner that the gas fumes or other objectionable elements may circulate freely there- 60 through into the chamber formed by the glass container 7 and registering on the filaments 12.

65 In order to provide suitable reflecting means for easily reading the tester when lowered into a manhole, or other similar position, it is preferred in this invention to provide a mirror reflector having adjustable means both perpendicularly and angularly of the lamp and means for clamping the reflector firmly in any desired position wherein numeral 13 designates a suitable supporting member for the reflector and adapted to be held in operable position by the two adjacent supporting rods for the 70 main body portion 1, such as rods 3 and 4. The supporting member 13 for the reflector 75 may be made of any desirable material and preferably of rod shape, having at one end threaded portions 14 and at the other end an element 15, which may be easily and manually operated for bringing the required tension when needed. The supporting member 13 is adapted to be rotatably mounted in a pair of bearings 16 and 17, which are 80 preferably integrally formed from a pair of sleeve portions 18 and 19, which are in turn slidably positioned on the rods 3 and 4 which support in part the main body 1 and base portion in spaced relationship. 85

The main body portion 20 of the reflector is adapted to be made of any suitable material, such as brass or otherwise, to conform with the type of material used in the supports 3 and 4 and supporting member 13. The main portion 20 consists of a frame section having turned in edges 21 for receiving in slidable relationship therewith a mirror portion 22 or other suitable reflecting element. In order to re-enforce the turned in portions 21 of the main portion 20, a cross brace 23 may be positioned in the rear of the mirror member 22 extending between the two free ends of the turned in edges in such a manner as not only to re-enforce the main portion 20 but also to act as an additional support for the mirror 22. Positioned along the lower edge of the main portion 20 and preferably integrally formed therewith is a tubular element 25 adapted to be rotatably mounted upon the supporting member 13 between the rod members 3 and 4 and the bearing portions 16 and 17, thereby providing a supporting means for the mirror 22 which may be easily adjusted to any desired position along the rods 3 and 4 and, at the same time, the mirror, being pivotally mounted on the member 13, may be adjusted at any desired angle with the perpendicular. In positioning the mirror upon the supporting member 13, it is merely necessary to release the threaded portion 14 of the member 13 from the co-operating threaded portion 24 of the bearing 16 and withdraw the rod 13 a sufficient distance through the bearing member 17 in order to admit the tubular element 25 into a location where the supporting member 13 may be inserted therethrough and again be brought into threaded relationship with the bearing 16, thereby providing a means by which the mirror may be firmly held under tension in any desired position along the rods 3 and 4, the reflecting mirror 22 being preferably located opposite the darkened or painted portion 8 of the glass container 7 and having the filaments 12 therebetween.

In operation, this invention provides a mirror reflector particularly adapted for aiding in the reading of lamp testers for gas fumes or the like. The gas tester, as herein described and claimed, may be used particularly in the coal regions for testing the gas in mines or otherwise, as well as for testing the gases in sewers through manholes and other similar places. The particular arrangement of the reflecting mirror in this invention permits the lamp to be lowered into a manhole or other place where there is supposed to be gas fumes and the mirror may easily be adjusted as described so as to aid in reading the registration regarding the presence of gas or otherwise.

This invention eliminates entirely the danger of being overcome with the gas

fumes, as often happens in cases where people have been obliged to enter into places of the type described.

It is to be understood that alterations and substitutions may be made in the above disclosure, including the drawings, within the scope of the appended claims without affecting the merits of this invention.

What I claim is:

1. In a gas lamp tester, a main body portion, a lower section, supporting members for holding the main body portion and lower section in spaced relationship, a transparent casing therebetween having a darkened section, a mirror reflector oppositely positioned to the darkened section, a lamp burner between the mirror reflector and the darkened section, filaments for registering gas fumes positioned above the burner and between the mirror and darkened section. 75

2. In a gas lamp tester, a main body portion, a lower section, supporting members for holding the main body portion and lower section in spaced relationship, a transparent casing therebetween having a darkened section, a mirror reflector oppositely positioned to the darkened section, a lamp burner between the mirror reflector and the darkened section, filaments for registering gas fumes positioned above the burner and between the mirror and darkened section, elements slidably positioned on the supporting members for adjusting the mirror reflector in the desired angular relationship to the burner and filaments. 90

3. In a gas lamp tester, a main body portion, a lower section, supporting members for holding the main body portion and lower section in spaced relationship, a transparent casing therebetween having a darkened section, a mirror reflector oppositely positioned to the darkened section, a lamp burner between the mirror reflector and the darkened section, filaments for registering gas fumes positioned above the burner and between the mirror and darkened section, elements slidably positioned on the supporting members for adjusting the mirror reflector in the desired angular relationship to the burner and filaments, comprising a tubular element for holding the mirror, a cross bar adjustably positioned between the supporting members for rotatably receiving the tubular element, clamping means for firmly holding the tubular element in fixed position along the supporting members. 105

4. In a gas lamp tester, a main body portion, a lower section, supporting members for holding the main body portion and lower section in spaced relationship, a transparent casing therebetween having a darkened section, a mirror reflector oppositely positioned to the darkened section, a lamp burner between the mirror reflector and the darkened section, filaments for registering gas fumes 125

positioned above the burner and between the mirror and darkened section, elements slidably positioned on the supporting members for adjusting the mirror reflector in the desired angular relationship to the burner and filaments, comprising a tubular element for holding the mirror, a cross bar adjustably positioned between the supporting members for rotatably receiving the tubular element, clamping means for firmly holding the tubular element in fixed position along the supporting members, consisting of a threaded portion at one end of the cross bar and an operating thumb member at the opposite end, the threaded end of the cross bar being adapted to cooperate with one of the supporting members in such a manner that when the thumb member is turned the tubular element and mirror may be released or clamped firmly in desired position between the supporting members.

In testimony whereof I affix my signature.
FRANK H. STAIR.
